United States Patent Office.

G. L. MILLER, OF DE WITT, NEW YORK.

Letters Patent No. 77,638, dated May 5, 1868.

IMPROVED WINDOW-CURTAIN FIXTURE.

The Schedule referred to in these Letters Patent and making part of the same.

TO ALL WHOM IT MAY CONCERN:

Be it known that I, G. L. MILLER, of De Witt, in the county of Onondaga, and State of New York, have invented a new and useful Improvement in Hanging Window-Curtains; and I do hereby declare that the following is a full, clear, and exact description thereof, which will enable those skilled in the art to make and use the same, reference being had to the accompanying drawings, forming a part of this specification.

This invention relates to that class of curtains which have a vertically-adjustable roller, for lowering the head of the curtain for ventilative purposes.

In the accompanying drawings, A is a movable curtain-roller, which is suspended by means of two cords, D D', running over pulleys b b', and connecting with a loaded tassel, C. The suspending-cords D D' take hold of the journals a of the curtain-roller, by means of links e e, the said journals rotating in these links. On the ends of the journals a are also eyes or swivels, f f, which run on guide-rods g g. The guide-rods g and swivels f steady the curtain when lowered, as shown, and prevent the roller from swaying and blowing about.

The weight of the curtain and roller is balanced by the loaded tassel C, so that it always remains in the position in which it is placed, and there is no liability for said roller to fall when the sustaining-cords become elongated by stretching, as heretofore.

When the roller is down for ventilating at the top of the window, as shown, the curtain can be raised most readily or lowered, by giving the tassel C a slight movement, but the ordinary tape, h, is also provided, and is used when the roller A is to remain fixed.

The sustaining-links e and swivels at each end of the roller can be made in one piece, instead of being made separate, as shown.

Having thus described my invention, what I claim as new, and desire to secure by Letters Patent, is—

The guide-rods g and swivels f, in combination with the vertically-adjustable roller A, as and for the purpose set forth.

The above specification of my invention signed by me, this 19th day of March, 1868.

G. L. MILLER.
